UNITED STATES PATENT OFFICE

2,036,742

AUTOMATIC WINDMILL REGULATOR

John C. Buck, Denison, Iowa

Application April 9, 1935, Serial No. 15,492

1 Claim. (Cl. 103—28)

This invention relates to means operable automatically by the action of water within a cistern from which water is being pumped by a windmill, so as to cease the pumping of water at desired times, to avoid the pumping of air into the water line and which air in the water line is troublesome as is well known.

Another object is to provide a construction wherein the regulation or control is effected through the operation of novel float means, which will insure pumping of the water in limited quantities at a time so as to avoid undue wear and strain on the windmill.

The more specific objects and advantages will become apparent from a consideration of the description following taken in connection with accompanying drawing illustrating an operative embodiment.

In said drawing:—

Figure 1 is a view partly in perspective and partly in vertical section illustrating the invention, and

Figure 2 is a view on an enlarged scale of the lower part of Figure 1.

Referring specifically to the drawing, 10 generally designates a conventional windmill mounted in the ground 11 adjacent a well 12 from which the windmill is adapted to pump water, suggested at 13, through a pipe 14, to water-works, a cistern or storage tank away from the windmill.

Said conventional windmill 10 has a shut-off mechanism 15, shown as controlled by a sliding element 16, so as to demesh the gearing 17 which normally causes the windmill to pump, or else controls means to place the windmill vanes 18 in a non-operating position, or in some other way shuts off the operation of the windmill. The sliding part 16 is operated by a link 19 pivoted thereto and pivoted at 20 to a lever 21, having an arm 22, suitably pivoted at 23 to a fixed part of the windmill. Normally the windmill is operative and a wire or cable extends from the lever 21 to the ground so that the wire may be manually operated to shut off the windmill. In lieu of such wire, however, I attach to the lever 21 a rod 24 having a hook 25 at its lower end. A chain 26 is connected to the hook 25 at any of the links thereof, and any of such links suspend a rod 27 through the medium of a hook 29, in the well 12. The links of the chain enable the rod 27 to be

disposed at various heights. A weight or abutment 30 is provided at the lower end of the rod 27 and freely slideable along the rod 27 is a float 31 constructed of laminated boards or any other desired material.

In the use of the device, the weight 30 is disposed at the depth in the well at which pumping operation of the windmill is to stop. Said float 31 has just enough buoyancy to float and as the water in the well 12 is pumped out and the water level lowered, the float descends down the rod or wire 27 until it strikes the stop or weight 30, so that such weight 30 with the weight of the float added thereto, is sufficient to pull down on the rod 27, chain 26, and rod 22, to shift lever 15, link 19, and slide 16 and accordingly actuate the shut-off mechanism of the windmill 15 to throw the windmill out of gear, or the vanes out of position or otherwise cause operation of the windmill to entirely cease. Thus the invention will stop the operation of the windmill when the water level in the well reaches a certain predetermined depth.

It will be realized that as soon as the float again rises, after shutting off the windmill, that the latter will be placed in gear again or rendered operative, so that the mill will pump a little at a time and thus be easier from the standpoint of wear, on the mill, as well as be very inexpensive and efficient.

Various changes may be resorted to provided they fall within the spirit and scope of the invention.

What is claimed is:—

In combination with a well and a windmill-operated pump in pumping communication therewith having a shut-off device, a rod suspended from said device having a weight adapted to be disposed in the well at the level at which operation of the mill is to cease, a float slideable relatively to said weight and into contact therewith to operate the cut-off through the combined weight of the weight and float, said weight being on a rod, a chain to which the rod is connected, a second rod, said second rod being connected to the chain and to the cut-off mechanism, said rod having hooks, and the links of said chain being selectively engageable with said hooks to regulate the depth of the weight.
